Bruno Wesselmann

UNITED STATES PATENT OFFICE.

BRUNO WESSELMANN, OF GÖTTINGEN, GERMANY.

METAL-SHEARING MACHINE.

SPECIFICATION forming part of Letters Patent No. 629,633, dated July 25, 1899.

Application filed December 8, 1898. Serial No. 698,653. (No model.)

To all whom it may concern:

Be it known that I, BRUNO WESSELMANN, a subject of the King of Prussia, German Emperor, residing at 58 Friedländer Weg, Göttingen, in the Province of Hanover, Kingdom of Prussia, Germany, have invented new and useful Improvements in or Connected with Metal-Shearing Machines, of which the following is a specification.

10 The present invention has for its object an improvement in the construction and shape of the framing of metal-shearing machines and in the manner of securing the lower blade in the same.

15 The accompanying sheet of drawings clearly illustrates my invention.

Figure 1 is a side elevation of the metal-shearing machine. Fig. 2 is a face view of the shaped plate before being bent to the required formation. Figs. 3, 4, and 5 are cross-sections showing various forms into which the bed-plate may be bent.

According to my invention I form the framing or stand from a single metallic plate of a suitable contour, and I bend or press the same to the required shape.

The improved framing or bed-plate, as indicated in the drawings, is such that the same may be readily formed from a single plate of metal. This metallic plate *a'*, the thickness or strength of which would vary according to the size and power of the shears, is shaped as shown in Fig. 2. The plate *a'* is then bent or pressed by suitable means at the points indicated by the dotted lines until it assumes the form shown in cross-section in Fig. 3 or that of Fig. 4. The bent-in portion *c* of the plate *a'* (shown in Fig. 3) and the bent-out portion *c* in Fig. 4 serve as the foot by means of which the shears are supported. If desired, the foot *c'* may be separate from and secured to the framing *a b*, as indicated in Fig. 5. With this improved formation of bed-plate the cutting-blades *m* and *m'* are so arranged relatively to each other that the lever *h*, to which the blade *m* is secured, lies in an angular recess formed by the bending back of the upper portion *a* of the bed-plate, the under portion *b* of the bed-plate carrying the fixed blade *m'*. By this arrangement the cut

portions *ff'* of the work *F* can both be conducted to the rear of the shears below the pivot-bolt *o* without necessitating any appreciable bending of the cut portions of the work. The feeding forward of the work is thus greatly facilitated, as only a slight amount of friction and springing of the cut plates is induced. In addition to the foregoing advantages the shears are strengthened by the improved formation of bed-plate or framing. They are light and can be constructed at a cheaper rate.

The lower blade *m'* is secured to the framing *a b c* by means of bolts *s*, which may be adjusted in vertical direction in slots *i*. The under edge of the blade rests upon set-screws *t t*, passing through block-bends *n*, screwed to the framing *a b c*. By this means the lower blade *m'* is securely fastened to the framing and so prevented from being displaced relatively to the movable blade *m* during the cutting operation and at the same time is capable of being tilted in either direction, to front or rear. By adjustment of the bolts *s* in the slots *i* the blade *m'* may be given such a position relatively to the movable blade *m* as is necessary for the particular material to be cut, and by screwing up or loosening the set-screws *t t*, as described, it can be held fixed in such position so that even under the strongest pressure displacement of the blade is prevented.

By having the upper front portion of the metallic plate cut away, as indicated by the cut-out in Fig. 2, a space is formed for receiving the shearing-blades, and the cut parts of the work can be carried backward or away from the blades without materially bending such work.

Having now particularly described and ascertained the nature of my said invention and in what manner the same is to be performed, I declare that what I claim is—

1. A metal-shearing machine comprising a stand or frame, having an upper vertical portion cut away at one end, a horizontal portion also cut away at one end, and a lower vertical portion, a stationary cutting-blade secured to the lower vertical portion adjacent to the cut-away end of the horizontal portion,

an operating-lever fulcrumed to the upper vertical portion and a movable cutting-blade carried thereby, as and for the purpose set forth.

5 2. A metal -shearing machine having a frame provided with a blade m' , a bolt-and-slot connection for adjustably securing the blade to the frame, and adjustable support-

ing-screws t for the blade at the lower edge of the latter substantially as described. 10

In testimony whereof I affix my signature in presence of two witnesses.

BRUNO WESSELMANN.
